C. ROSENTHAL.

DRINKING CUP HOLDER FOR WATER BOTTLES.
APPLICATION FILED SEPT. 9, 1919.

1,349,473.

Patented Aug. 10, 1920.

UNITED STATES PATENT OFFICE.

CHARLES ROSENTHAL, OF NEW YORK, N. Y.

DRINKING-CUP HOLDER FOR WATER-BOTTLES.

1,349,473.

Specification of Letters Patent. Patented Aug. 10, 1920.

Application filed September 9, 1919. Serial No. 322,619.

To all whom it may concern:

Be it known that I, CHARLES ROSENTHAL, a citizen of the United States, and a resident of the city of New York, borough of Manhattan, in the county of New York and State of New York, have invented a new and Improved Drinking-Cup Holder for Water-Bottles, of which the following is a full, clear, and exact description.

10 This invention relates to improvements in drinking cup holders for water bottles, and more particularly to a device adapted to clamp upon the inverted upper end of a water bottle when the latter is in position 15 in a water cooler, an object of the invention being to provide a device of the character stated, which will effectually support a carton or box containing a column of drinking cups in convenient position for use.

20 A further object is to provide a device of the character stated, which can be folded or collapsed so as to allow a large number of the devices to be conveniently packed for shipment.

25 A further object is to provide a device of the character stated, which will be extremely cheap to manufacture, which will be strong and durable in use, and which will most efficiently perform the functions for 30 which it is intended.

With these and other objects in view the invention consists in certain novel features of construction, and combinations and arrangements of parts, as will be more fully 35 hereinafter described and pointed out in the claims.

In the accompanying drawings—

Figure 1 is a view in elevation illustrating my improvements in operative position 40 on a water bottle;

Fig. 2 is a top plan view with the box or carton removed;

Fig. 3 is a view in side elevation of the device removed from the bottle and the 45 members folded together;

Fig. 4 is an edge view of Fig. 3;

Fig. 5 is a plan view of Figs. 3 and 4; and

Fig. 6 is an enlarged fragmentary view 50 in section on the line 6—6 of Fig. 3.

My improved device comprises four spring wire members 1, each member having a straight vertical intermediate portion 2 confined within a coupling sleeve 3. This coupling sleeve 3 permits a free turning movement of the members therein, secures all

of the members together and provides a support or standard to strengthen the device.

The members 1 above the sleeve 3 are bent outwardly and disposed horizontally, 60 as shown at 4, are then bent upwardly and disposed vertically, as shown at 5, and at their upper ends are bent forming horizontal right angle hooks 6.

The members 1 below the coupling 3 are 65 bent outwardly forming horizontal portions 7 adapted to rest on top of an inverted bottle 9 and the ends of the wires are bent downwardly and inwardly forming hooks 8 to grip the sides of the bottle. 70

As above stated, this device is adapted for use on inverted bottles while the latter are in position on water coolers and the device can be readily inserted on the bottle by springing the hooked ends 6 over the same 75 as illustrated.

10 represents a box or carton containing a column of drinking cups 11 and this box is supported on the horizontal portions 4 of the members and the corners of the box are 80 confined by the hook 6 so that the box is securely held in an upright position in convenient location for the cups.

One of the most important features of my 85 invention is the independent members connected by the coupling sleeve 3 which permits the members to move relative to each other when not in operative position. Hence, the members can be folded against each other, as shown in Figs. 3, 4, 5 and 6, and 90 will lie comparatively flat and permit a large number of the devices to be packed in a relatively small space.

Various slight changes may be made in the general form and arrangement of parts 95 described without departing from the invention, and hence I do not limit myself to the precise details set forth but consider myself at liberty to make such changes and alterations as fairly fall within the spirit 100 and scope of the appended claims.

I claim:

1. A device of the character stated, comprising a plurality of spring wire members, 105 bottle engaging hooks formed on the lower ends of said members, the upper ends of said members bent forming a carton support, and a coupling device connecting the intermediate portions of the members holding them together and permitting independent movement of the members. 110

2. A device of the character stated, com-

- prising a plurality of spring wire members, bottle engaging hooks formed on the lower ends of said members, the upper ends of said members bent forming a carton support, 20
- 5 5. a coupling device connecting the intermediate portions of the members holding them together and permitting independent movement of the members, said coupling device comprising a vertically positioned sleeve, 25
- 10 and said members having vertical intermediate portions confined in the sleeve.
3. A device of the character stated, comprising a plurality of spring wire members, all of said members having straight vertical 30
- 15 intermediate portions, a vertically disposed coupling sleeve confining the said intermediate portions of the members, bottle engaging hooks on the lower ends of the mem-

bers, and the upper ends of said members bent forming a carton support.

4. A device of the character stated, comprising a plurality of spring wire members, all of said members having straight vertical intermediate portions, a vertically disposed coupling sleeve confining the said intermediate portions of the members, bottle engaging hooks formed on the lower ends of the members, the upper ends of the members above the coupling bent outwardly and positioned horizontally, then projected upwardly and vertically and having horizontal right angle hooks at their upper ends adapted to engage the corners of the box supported on the said horizontal portions. 25

CHARLES ROSENTHAL.
